RAYMOND H. OLLEY, OF SYRACUSE, NEW YORK, ASSIGNOR TO CROUSE-HINDS COMPANY, OF SYRACUSE, NEW YORK, A CORPORATION OF NEW YORK.

ELECTRIC SWITCH.

Application filed December 4, 1923. Serial No. 678,549.

To all whom it may concern:

Be it known that I, RAYMOND H. OLLEY, a citizen of the United States, and a resident of Syracuse, in the county of Onondaga and State of New York, have invented a certain new and useful Electric Switch, of which the following is a specification.

This invention relates to electric switches, and has for its object a particularly simple and efficient switch or mechanism thereof, by which the switch arm or arms are not only brought into and out of engagement with the switch contacts by a quick break action, but are also brought into and out of engagement with the contacts and especially into engagement therein by a wiping movement, whereby the contacting surfaces are cleaned.

This invention consists in the novel features and in the combinations and in the constructions hereinafter set forth and claimed.

In describing this invention reference is had to the accompanying drawings, in which like characters designate corresponding parts in all the views.

Figure 1 is a vertical sectional view of a switch embodying my invention, the casing or housing being also shown.

Figure 2 is an elevation of the switch and housing, the other parts being omitted.

Figure 3 is a vertical sectional view partly in elevation of parts shown in Figure 2.

Figure 4 is an inverted plan view of parts seen in Fig. 1.

This switch comprises generally a base having a switch contact or contacts thereon, an operating member movable relatively to the base, comprising an arm or arms mounted to move into and out of engagement with the contact or contacts, and also movably laterally to have a wiping effect on the contacts as the switch arms move into and out of engagement with the contacts especially out of engagement, an operating member movable relatively to the switch member, and connections operated by the operating member for moving the switch member and said arms. The switch arms are preferably spring pressed in one direction or are spring metal so that the spring is inherent therein, presses them laterally in one direction, and such spring also moves the switch member toward and from the contacts with a snap action, after the

spring arms have been tensioned by the operating member.

In the illustrated embodiment of this switch the operating member is movable rectilinearly at an angle, as a right angle to the base, and is slidably mounted, and the switch member is movable lengthwise of the operating member and reversely relatively thereto. The switch arm or arms extend lengthwise of the operating member toward the base.

1 designates the base which is formed of suitable insulating material, 2 are the contacts mounted on the base, these contacts being the end faces of conductors or plugs 3, extending through the base and being here shown as having binding screws 4 at their outer or lower ends.

5 is the operating member here shown as a rod slidable through in a passage 6, in the base between the contacts 2, and having a stem 7 provided with a knob or handle 8 at its upper end. The stem extends through a neck 9 of a suitable housing 10, the housing comprising a recess 11 opening through one end of the housing. The base is fitted within the open end of the housing and as the base 1 is cylindrical in form, the recess 11 is cylindrical at least at its open end. A suitable lining 12 of insulation is fitted within the housing around switch mechanism.

This housing is here shown as formed with a base flange 13, by means of which it is mounted upon a support as for instance an outlet box, it being secured to the outlet box or the support by screws extending through openings 14 in the base flange. The base is secured in position by laterally extending lugs 15, lapping the lower face of the base flange 14 and secured thereto by screws extending through holes in the base flange and threading into the holes 16 in the lugs.

The stem 7 of the operating member 5 also moves through or is guided in an opening in a yoke or frame 17, supported by the base so that the switch itself is a unit independent of the housing.

The switch member here illustrated is mounted to slide lengthwise of the operating member 5 reversely relatively thereto, so that when the operating member moves down then such member moves in the reverse direction or upwardly. The switch mem-

ber comprises spring arms 18 extending in a general direction lengthwise of the operating member toward the base 1.

- The switch member here shown comprises 5 one or more plates 20, 21 having openings therein for the operating member 5, the part of the operating member along which the switch member slides being non-circular or square, the holes in the plates are also 10 non-circular or square. The plate 20 is of metal and the other plate 21 is usually of insulating material. Each switch arm 18 is in the general form of a bow spring and the tension of the spring arms tends to move 15 the free ends thereof inwardly toward the operating member 5. Each arm spring is formed with a contact or foot 23 at the lower end for engagement with the contact 2. The switch arms 18 are usually formed 20 from a single piece of metal, the intermediate part of which is clamped between the plates 20 and 21, and provided with a hole through which the operating member extends.
- 25 The connections operated by the operating member 5 comprise links 24 pivoted at like ends at 25 to the operating member 5, and at the other or outer ends to the switch arms 18, the outer ends being usually in the 30 form of pins extending radially through rollers 26 which fit in sockets 27 formed in the arms 18, the pins extending through slots in the sockets.

The operating member is usually formed 35 with a lengthwise slot 28 and the inner ends of these links extend into the slot.

During downward movement of the member 5 the joint 25 of the links are moved 40 downwardly from the position shown in Fig. 1, to that shown in Fig. 2, and first press the arms 18 outwardly and when the ends of the arms pass the dead center line of the links, that is a straight line passing through the pivots 25, 26, the switch will snap upwardly 45 with a quick action owing to the resiliency of the members 18. During upward movement of the member 5 the switch arms are spread apart until the links pass through the dead center line when the arms are moved 50 downwardly and inwardly with a snap action to engage the contacts 2, the feet wiping on such contacts, and in so doing make a perfect contact.

What I claim is:

- 55 1. In a switch, the combination of a base having a contact thereon, a switch arm mounted to shift toward and from the base into and out of engagement with the contact, the switch arm having a portion extending 60 parallel to the direction of the shifting movement and movable laterally relatively to the shifting movement thereof, whereby the switch arm has a wiping engagement with the contact, and an operating member movable in a direction substantially parallel

to the former movement of the switch arm, and connections between the operating member and the switch arm to effect the shifting and lateral movements thereof.

2. In a switch, the combination of a base, 70 a contact thereon, a switch arm and an operating member, the switch arm being mounted to move rectilinearly toward and from the base into and out of engagement with the contact, and the switch arm extending parallel to the operating member and having an engaging end movable laterally relatively to its rectilinear movement, whereby the switch arm has a wiping movement on the contact, the operating member being movable in a 80 general direction parallel with the switch arm, and connections between the operating member and the switch arms to effect such movements.

85 3. In a switch, the combination of a base, a contact thereon, a switch arm and an operating member, the switch arm being mounted to move rectilinearly toward and from the base into and out of engagement with the contact, and the switch arm extending parallel to the operating member and having an engaging end movable laterally relatively to its rectilinear movement, whereby the switch arm has a wiping movement on the contact, the operating member being movable in a 90 general direction parallel with the switch arm, and connections between the operating member and the switch arm to effect such movements, such connections comprising a 95 link pivoted at one end to the operating member and extending laterally therefrom, and pivotally connected at its other end to the switch arm.

100 4. In a switch, the combination of a base, a contact thereon, a switch member movable rectilinearly toward and from the base, and comprising a switch arm having a lateral movement relative to the rectilinear movement, whereby the switch arm has a wiping engagement with the contact, an operating member movable in a direction parallel to the switch member, the switch member being slidably mounted on the operating member, and connections between the operating member and the switch arm to effect such movements of the switch member and the switch arm.

105 5. In a switch, the combination of a base, a contact thereon, a switch member movable rectilinearly toward and from the base and comprising an arm having a lateral movement relative to the rectilinear movement, whereby the switch arm has a wiping engagement with the contact, an operating member movable in a direction parallel to the switch member, the switch member being slidably mounted on the operating member, and connections between the operating member and the switch arm to effect such movements of the switch member, and said arm,

such connections being arranged to move the switch member reversely relatively to the operating member.

6. In a switch, the combination of a base, a contact thereon, a switch member movable rectilinearly toward and from the base, and comprising a switch arm having a lateral movement relative to the rectilinear movement, whereby the switch arm has a wiping engagement with the contacts, an operating member movable in a direction parallel to the switch member, the switch member being slidably mounted on the operating member, and connections between the operating member and the switch arm to effect such movements of the switch member, such connections being arranged to move the switch arm reversely relatively to the operating member, and comprising a link pivoted at one end to the operating member and at its other end to the switch arm.
7. In a switch, the combination of a base having a contact therein, a switch arm mounted to move toward and from the base into and out of engagement with the contact, the switch arm being spring-pressed and tensioned to have a lateral movement relatively to its movement toward and from the base, whereby the switch arm has a wiping engagement with the contact, and operating member, and connection between the operating member and the switch arm to effect such movement and tension the spring pressed portion.
8. In a switch, the combination of a base, a contact thereon, a switch member movable rectilinearly toward and from the base, and comprising a switch arm provided with a spring pressed portion having a lateral movement relative to the rectilinear movement, whereby the switch arm has a wiping engagement with the contacts, an operating member movable in a direction parallel to the switch member, the switch member being slidably mounted on the operating member, and connections between the operating member and the switch arm to effect such movements of the switch member, such connections being arranged to move the switch arm reversely relatively to the operating member, and comprising a link pivoted at one end to the operating member and at its other end to the switch arm.
9. In a switch, the combination of a base, a reciprocally movable operating member movable at an angle to the base, a switch member slideable lengthwise of the operating member, and comprising a switch arm capable of movement laterally relatively to the operating member and connections operated by the operating member for moving the switch member into and out of engagement with the contact and also to move the switch arm laterally whereby the switch arm has a wiping engagement with the contact.
10. In a switch, the combination of a base, a reciprocally movable operating member movable at an angle to the base, a switch member movable lengthwise of the operating member and reversely relatively thereto, and comprising a laterally movable switch arm supported and connections operated by the operating member for moving the switch member toward and from the contact and also moving the switch arm laterally, whereby the switch arm moves into and out of engagement with the contact with a wiping movement.
11. In a switch, the combination of a base, an operating member reciprocally slideable relatively to the base at an angle thereto, a switch member slideable lengthwise of the operating member and comprising resilient switch arms extending lengthwise thereof toward the base and being movable laterally relatively to the operating member and links pivoted at like ends to the operating member and at their other ends to said arms.

In testimony whereof, I have hereunto, signed my name, at Syracuse, in the county of Onondaga, and in the State of New York, this 15th day of November, 1923.

RAYMOND H. OLLEY.
